MIKE N. HURLEY, OF WHITTIER, CALIFORNIA

LIFT FOR AUTOMOBILE WINDOW GLASS

Application filed March 27, 1929. Serial No. 350,267.

This invention relates to window activating mechanisms, and more particularly to a device for effecting sliding movement of a window in respect to its supporting structure.

An object of the invention is the provision of a device adapted to be installed within a relatively small space, and operatively connected to a sliding window so as to effect opening or closing of that window. As such, the device is peculiarly adapted for use in connection with the windows of vehicles, because of the comparatively small space within which the operating devices for vehicle windows, must be confined.

A further object is the provision of a quick acting and irreversible window activating mechanism, the purpose being to provide a mechanism by means of which the window 20 may be moved from fully opened to fully closed position, or vice versa, by rotating an operating handle through substantially only 90°, in contradistinction to the conventional window operating mechanism which requires that the operating handle be rotated several times to effect moving of the window from one extreme position to the other.

The invention possesses other objects and advantageous features, some of which, with those enumerated, will be set forth in the following description of the invention's particular embodiment which is illustrated in the drawings accompanying and forming a part of the specification.

Referring to the drawings:

Figure 1 is an inside elevation of an automobile door, portions of the upholstery having been broken away to better disclose the nature of the invention. The window and operating mechanism associated therewith, are shown in the positions assumed thereby when the window is fully closed.

Fig. 2 is a view similar to Fig. 1, with the window moved to fully opened position.

Fig. 3 is an enlarged, detail vertical sectional view taken upon the line 3—3 of Fig. 1, with the direction of view as indicated.

Fig. 4 is an enlarged, detail vertical sectional view taken upon the line 4—4 of Fig. 50 2, with the direction of view as indicated.

In terms of broad inclusion, the window activating mechanism of the present invention, comprises a spiral rod mounted for rotary movement about the axis of the spiral described by the rod, and operatively connected to a sliding window to effect opening or closing of the window when the rod is rotated.

Specifically describing the invention in its preferred embodiment, it is herein shown and described as being mounted within a vehicle door 6 such as that conventionally employed upon closed automobile bodies. This door comprises an outer panel 7, and upholstery 8 upon the inner face thereof, these parts being supported by a suitable framework 9. An aperture 11 is formed in the upper portion of the door 6, and this aperture is adapted to be optionally closed or opened by a sliding window 12. This window may be guided in any convenient manner, and since the guiding means for the window, constitute no portion of the present invention, they have not been herein detailed.

A channel-shaped strip 16 is affixed to the lower edge of the window 12, in any convenient manner. Preferably an insert 17 of felt or other suitable cushioning material, is interposed between the strip 16 and the window, as indicated upon Fig. 4. This strip 16 is provided with a U-shaped bracket 18, the legs 19 of which extend downwards from the under side of the strip 16. Spaced rollers 21 are journaled in the bracket 18, between the legs 19 thereof.

A shaft 22 is journaled within a brace 23 which forms a portion of the framework 9 of the door, and extends across the space 24 inside the door 6, between the upholstery 8 and the exterior panelling 7. An additional brace 26 may extend across the framework 9, to provide a seat for a bracket 27 within which the inner end 28 of the shaft 22 is journaled. A nut 29 and washer 31 are secured to the inner end 28 of the shaft 22, inside the bracket 27, to restrain the shaft 22 against longitudinal displacement. The shaft 22 extends through the upholstery 8 and through an elongated collar 32, so that its inner end 33 is spaced far enough from the upholstery

8, to permit easy operation of a handle 34 which is rigidly attached to the inner end 33 of the shaft 22. A nut 36 secured to the end 33 of the shaft, prevents displacement of the handle 34 therefrom.

5 A rod 37 is rigidly attached to the shaft 22, as by welding, and extends therefrom in the form of a spiral, as clearly shown upon Figs. 1 and 2. This rod passes between the rollers 21, with the result that when the shaft 22 is turned, carrying with it the rod 37, the window 12 is either pulled toward the shaft 22, or pushed therefrom, depending upon the direction of rotation.

10 Preferably the plane of the spiral described by the rod 37, coincides with that of the window 12, with the result that the entire operating mechanism may be received within a space 24 within the door, of minimum thickness.

15 In its preferred form, the spiral described by the rod 37, coincides with the mathematical curve delineated as a spiral of Archimedes, the distinguishing feature of which, 20 is that the angle varies directly as the radius vector. This type of spiral is most desired, because a constant rate of rotation of the shaft 22 will result in a constant rate of movement of the window 12, if this particular spiral is employed.

25 It is also desirable to position the shaft 22, not directly under the bracket 18, but far enough to one side of a point directly therebeneath, to bring that portion 41 of the rod 37, which is received between the rollers 21, into substantial parallelism with the lower edge of the window 12. As a result of this 30 feature, a mechanical advantage is developed, which assists in raising the window 40 with a lesser amount of force exerted upon the shaft 22, because when the shaft 22 is turned to the right, as viewed upon Fig. 1, that portion 41 of the rod 37, which, at that 45 time is between the rollers 21, will then be given a slight upward movement, whereas if the shaft 22 were directly below the bracket 18, the portion 41 of the rod 37 would not move upwards, but would move in a direction truly parallel to the under side of 50 the window, developing no upward push other than the wedging action resulting from the increased radius vector of the spiral.

55 A coil spring 42 is under tension between the frame 9 and the rod 37, urging the rod and shaft 22 to rotate in that direction which will result in raising the window 12. Preferably this spring is proportioned and positioned so that the turning moment set up in the rod 37 by the downward pressure of the 60 window 12, is substantially neutralized by the force of the spring 42.

65 The operation of my improved window activating mechanism is believed obvious from the above description of its constituent parts. As the shaft 22 is turned to the right

as viewed upon Fig. 1, the distance between the shaft 22 and that portion 41 of the rod 37, disposed between the rollers 21, is increased, pushing the window 12 upwards.

Conversely, rotation of the shaft in the opposite direction, will result in pulling the window downwards to open the aperture 11. It is apparent therefore, that movement of the window from fully opened to fully closed position, and vice versa, may be effected by imparting to the handle 34, practically only 90° of rotation, in contradistinction to the conventional window activating mechanisms which require that the handle be turned several times to move the associated window from one extreme position to the other. On account of the relatively small angle between the lower edge of the window 12 and a line drawn tangent to that portion 41 of the rod 37 disposed between the rollers 21 at any particular time, any force exerted downwards upon the rod 37 by the upper roller 21, will develop a very small component tending to produce rotation of the shaft 22. This feature results in making the device irreversible so that the window can not be opened by any means other than by turning the handle 34.

70 It is to be understood that the details of the invention as herein disclosed, are subject to alteration within the spirit or scope of the appended claims.

75 I claim:

1. A device for moving a window slidably mounted in a supporting structure, said device comprising a curved rod mounted for rotary movement about a fixed axis, said rod being slidably engaged with said window, and means for turning said rod, said turning means being associated with the pivoted end of the rod.

100 2. A device for moving a window slidably mounted in a supporting structure, said device comprising a curved rod mounted for rotary movement about a fixed axis and in the plane of movement of the window, said rod being slidably engaged with said window, and means for turning said rod, said turning means being associated with the pivoted end of the rod.

110 3. A device for moving a window slidably mounted in a supporting structure, said device comprising a shaft journaled in said supporting structure, a rod rigid therewith and extending spirally therefrom, a bracket rigid with said window and engaged with said rod, and means for turning said shaft.

115 4. A device for moving a window slidably mounted in a supporting structure, said device comprising a shaft journaled in said supporting structure and extending perpendicularly to the plane of said window, a rod rigid with said shaft and extending spirally therefrom, said rod being disposed in a plane to which said shaft is perpendicular, means

slidably inter-connecting said rod and said window, and means for turning said shaft.

5. A device for moving a window slidably mounted in a supporting structure, said device comprising a shaft journalled in said supporting structure and extending perpendicularly to the plane of said window, a rod rigid with said shaft and extending spirally therefrom, said rod being disposed in a plane 10 to which said shaft is perpendicular, said window being supported on said rod, means for turning said shaft, and spring means urging said shaft into rotary movement in that direction which will result in raising 15 said window.

6. A device for moving a window slidably mounted in a supporting structure, comprising a U-shaped bracket rigid with said window, a pair of spaced rollers journalled in said bracket between the legs thereof, a shaft journalled in said supporting structure in perpendicularity with the plane of said window, said shaft extending through a wall 20 of said structure and across a space inside the structure, a spiral rod rigid with said shaft within said space, said rod passing between said rollers and being disposed in a plane to which said shaft is perpendicular, and a handle rigid with the outer end of said 25 shaft.

7. A device for moving a window slidably mounted in a supporting structure, comprising a U-shaped bracket rigid with said window, a pair of spaced rollers journalled 30 in said bracket between the legs thereof, a shaft journalled in said supporting structure in perpendicularity with the plane of said window, said shaft extending through a wall of said structure and across a space inside the structure, a spiral rod rigid with said shaft within said space, said rod passing between said rollers and being disposed in a plane to which said shaft is perpendicular, a handle rigid with the outer 35 end of said shaft, and means urging said shaft to rotate in that direction effecting raising of the window.

8. A device for moving a window slidably mounted in a supporting structure, comprising a U-shaped bracket rigid with said window, a pair of spaced rollers journalled in said bracket between the legs thereof, a shaft journalled in said supporting structure in perpendicularity with the plane of said window, said shaft extending through a wall of 50 said structure and across a space inside the structure, a spiral rod rigid with said shaft within said space, said rod passing between said rollers and being disposed in a plane to which said shaft is perpendicular, a handle rigid with the outer end of said shaft, and a spring interposed between said rod and said supporting structure urging said shaft to rotate in that direction effecting raising of 55 the window.

9. A device for moving a window slidably mounted in a supporting structure, comprising a U-shaped bracket rigid with said window, a pair of spaced rollers journalled in said bracket between the legs thereof, a shaft journalled in said supporting structure in perpendicularity with the plane of said window, said shaft extending through a wall of said structure and across a space inside the structure, a spiral rod rigid with said shaft within said space, said rod passing between said rollers and being disposed in a plane to which said shaft is perpendicular, a handle rigid with the outer end of said shaft, and a spring interposed between said rod and said supporting structure, said spring being proportioned and disposed to neutralize the torque which would otherwise be exerted upon said shaft by the weight of the window.

10. A device for moving a window slidably mounted in a supporting structure, comprising a U-shaped bracket rigid with said window, a pair of spaced rollers journalled in said bracket between the legs thereof, a shaft journalled in said supporting structure in perpendicularity with the plane of said window, said shaft being disposed below and to one side of said bracket and extending through a wall of said structure and across a space inside the structure, a spiral rod rigid with said shaft within said space, said rod passing between said rollers and being disposed in a plane to which said shaft is perpendicular, a handle rigid with the outer end of said shaft, and a spring interposed between said rod and said supporting structure urging said shaft to rotate in that direction effecting raising of the window.

In testimony whereof I have signed my name to this specification.

MIKE N. HURLEY.
